(57) **CLAIM**

The ornamental design for a shoelace ornament, as shown and described.

DESCRIPTION

FIG. 1 is a front elevational view of shoelace ornament showing my new design;

FIG. 2 is a front elevational view thereof, attached to a left shoelace on a shoe;

FIG. 3 is an enlarged rear left perspective view thereof, attached to a shoelace;

FIG. 4 is a rear perspective view thereof, attached to a shoelace; and,

FIG. 5 is a rear view thereof attached to a shoelace, the two shoelaces tied together into a bow to secure the ornament in place.

The left shoe and shoelaces are shown in broken lines for illustrative purposes only and form no part of the claimed design.
